UNITED STATES PATENT OFFICE.

BURTON W. KENDALL, OF NEW YORK, N. Y., ASSIGNOR TO WESTERN ELECTRIC COMPANY, INCORPORATED, OF NEW YORK, N. Y., A CORPORATION OF NEW YORK.

MONITORING SYSTEM.

Application filed September 5, 1919. Serial No. 321,900.

To all whom it may concern:

Be it known that I, BURTON W. KENDALL, a citizen of the United States, residing at New York, in the county of New York, State 5 of New York, have invented certain new and useful Improvements in a Monitoring System, of which the following is a full, clear, concise, and exact description.

This invention relates to signaling, and 10 more particularly to transmitting and receiving circuits having flexibility whereby they may be readily adjusted for different signals. The invention covers also arrangements for connecting said circuits to a line 15 or to a repeater, and such other features as will be described in the following specification and included in the accompanying claims.

A more specific aspect of the invention relates to repeater circuits for multiplex signaling employing carrier currents on wires, and particularly to a means for monitoring telegraphic and telephonic messages at the 20 repeater station. By means of the invention 25 messages that are being repeated in either direction may be received at the repeating station, and messages may also be sent over either line from the repeating station through any channel of either line.

The invention will be better understood 30 from the drawings in which Fig. 1 is a schematic diagram of circuits for monitoring telegraphic messages according to the invention; and Fig. 2 shows means for monitoring telephonic messages.

Main lines 1, 2 and 1, 2 may be carrier 35 transmission lines for transmitting several current waves differing in frequency and forming communication channels 40 through which messages are conveyed in the form of modulations of the respective carrier waves. Each line 1, 2 terminates at the repeater station shown in means for coupling to the input of one repeater for repeating 45 into the other line, and to the output of another repeater for receiving a message being repeated from the other line. Since all this apparatus is entirely symmetrical, a double 50 series of reference characters is used, and the following description may apply equally well to one repeater and line or to the other

repeater and line. The path of the repeated message will first be traced through from one line 1, 2 to the other.

Currents incoming from line 1, 2 pass 55 through the coils 3, 4, 5 and 6, and in part through the coil 17 bridged across the line. By means of the coupling between coil 17 and a coil 18, the incoming currents are impressed across a resistance 19 forming a 60 potentiometer for the input terminals of the first repeating amplifier. By means of the sliding contact 21, the voltage impressed on the input of the first amplifier 20 may be regulated. Amplifier 20 is shown as of the 65 thermionic type, comprising an enclosure in which are a hot cathode or filament 22, a grid 23 and a plate or anode 24, or their equivalents. The filament is supplied with heating current from battery 25, and plate 70 potential is supplied from battery 26 connected to the filament and to the plate 24 through a choke impedance 27. The normal potential of the grid 23 with respect to the filament is fixed by a battery 28. A condenser 29 affords a low impedance path for the variation currents, and acts as a blocking condenser to prevent flow of direct current from battery 26 through coil 27 and the grid resistance 32 of the second-stage 75 amplifier. Resistance 32 permits the normal potential of the grid 31 of the second-stage amplifier 30 to be fixed by battery 33, relative to the filament, but is sufficiently large 80 not to act as a shunt for the output waves 85 from amplifier 20. Amplifier 30 may be of the same general type as amplifier 20, and act in a similar manner to impress the transmitted waves in amplified form through condenser 34 upon coils 11 and 12. Each line 90 1, 2 is provided with a net having electrical characteristics equivalent to those of the line. Coils 3 and 4 are also similar to each other and to coils 9 and 10, and coils 5, 6, 7 and 8 are likewise similar to one another. 95 By this arrangement the repeated waves from output windings 11 and 12 are fed into the outgoing line without affecting the input of the other side of the two-way repeater. Grounded shields 35, 35 are provided to protect against disturbances due to 100 capacity effects between the coil windings.

2 Thus far the description has been concerned merely with the repeating of the high-frequency modulated carrier currents between the main lines 1, 2 and 1, 2. The 5 provisions for monitoring the repeated messages will now be described.

Coils 3 and 9 are for the purpose of coupling to the coils 13 and 14, which latter coils are included in circuit with a coil 15. Coils 10 4 and 10 may be included in the coupling for coils 13 and 14. Coupled to coil 15 is a coil 16 in a circuit leading in one case to jack J_1 and in the other case to jack J_2 . A load is 15 normally present on the transformer 15, 16 in the form of an impedance 36 across the terminals of coil 16. A plug P is provided for inserting into either jack J_1 or J_2 to couple the telegraph monitoring apparatus to one or the other line through the corresponding coil 15, 16. The telegraph monitoring apparatus comprises tuning circuits 20 connected to plug P for tuning to a desired channel frequency, a generator and transmitter for sending over the desired channel, 25 a receiver circuit for receiving on any channel, and a switch for throwing either the transmitting circuit or the receiving circuit into communication with the tuning circuits and plug P.

30 The transmitting circuit comprises a generator with a key for controlling its output and an amplifier in its output circuit. A generator 40 of the thermionic-relay type is shown having a coupling between its output and input circuits. It comprises an enclosure in which may be a hot cathode, or other source of electrons, shown as filament 41, a plate or anode 42, and a grid or impedance-controlling element 43. Heating current for the filament is supplied from battery 44, through a regulating resistance. Plate potential is furnished by battery 45 connected on one side to the filament and on the other side to the plate through a suitable impedance 46. A space current is thus caused to flow between the heated filament 41 and the plate 42, and any variations in this current find a path through the condenser 47 of large capacity, and in part, 45 through inductance 48 back to the filament. In shunt to the inductance 48 are (when contact 49 is closed) an inductance 50 and a variable capacity 51. This combination of inductance and capacity 48, 50 and 51 may be tuned by adjusting condenser 51. The grid 43 is connected to this tuned circuit so that if there are oscillations in the tuned circuit, the potential of the grid will be periodically varied accordingly, and these variations of grid potential will cause corresponding current variations to flow in the plate circuit through condenser 47. A portion of this output current will be fed back to coil 48, as described, and the remaining portion will flow through the power-output

branch including the potentiometer resistance 52. The energy fed back to the input circuit of the generator will be sufficient to cause the continued generation of oscillations, the frequency of which, if contact 49 is closed, may be controlled by adjustable condenser 51. By means of the sliding contact on the potentiometer resistance 52, the maximum potential to be impressed upon the grid 53 of the amplifier 55 by the output oscillations from the generator may be chosen. The amplifier may be similar in construction to the thermionic element of generator 40, and may comprise an enclosure with a filament 54 heated by current from battery 44, a plate 56, and a grid 53 already mentioned. When the transmitting circuits are being used, a switch S is closed on the left side, marked T, and the output circuit of amplifier 55 then may be traced from plate 56 through the upper side of switch S through coil 57 and condenser 58, in parallel, through the lower side of switch S, plate battery 45 to filament 54 and through the space portion to plate 56 again. The amplified oscillations from the generator 40 are thus impressed on coil 57 when the switch S is thrown to transmitting position. If it is desired to transmit over the line 1, 2 at the left, the plug P is inserted in jack J_1 . The springs of the jack are spread so that the impedance 36 is removed from across the jack and the jack springs are now connected through the tip and ring contacts of plug P to the series resonant circuit comprising inductance 59 and condenser 60. By means of condenser 60, the circuit including coil 16 and elements 59 and 60 may be tuned to the frequency of the channel over which it is desired to transmit. The coupling between coils 57 and 59 may also be adjusted. The condenser 58 permits the circuit 57, 58 to be tuned to the frequency being transmitted. By means of variable condenser 51, the frequency of the generated wave may be adjusted to the proper channel frequency. With these adjustments made and the switch S closed to the transmitting side, a continuous wave of the selected carrier frequency will be impressed through coils 57, 59 and 115 16, 15 upon coils 13 and 14, as long as contact 49 is closed. Contact 49 may be controlled in any suitable manner and is shown as operated by the armature of the relay 61, which is in turn controlled by a circuit including battery 62 and a key K, so that with key K closed, contact 49 is closed. If now the key is opened, contact 49 is opened, and the condenser 51 is removed from the tuned circuit controlling the input of the generator. The shunt capacity of the coils 48 and 50 is comparatively very small and the frequency of the generator immediately mounts up to a relatively very high value, as soon as condenser 51 is removed from the circuit. 130

These high-frequency oscillations are prevented from reaching the coils 13 and 14 by the combination of tuned circuits including the inductances 57, 59 and condensers 58 and 60. The result is that with key K closed a continuous carrier wave is impressed on the line 1, 2, through coils 13, 14, associated with coils 3, 4, 9 and 10, and that with key K open, no current is transmitted to the line 1, 2. By virtue of the balance of the line and the net and the coils 3 to 10 inclusive, as to the terminals of coil 17, as previously explained, the current thus transmitted causes no disturbance to the input 15 coil 17 of the repeater. If the plug P had been inserted into jack J₂, the transmission could be effected into line 1, 2 at the right. Condensers 51, 58 and 60, together with the inductances, may have such range of adjustment 20 as to permit the monitoring set to communicate over any channel. When plug P is removed from the jack, impedance 36 is substituted across the springs of the jack in place of the circuit connected to the plug, 25 in order better to maintain the existing balance of the line and net work.

The receiving side of the monitoring set is shown as comprising a two-stage amplifying and a detecting circuit controlling a 30 relay which may in turn control a sounder or other receiver or recorder. In the form shown, the first two stages 65 and 75 are thermionic amplifiers, and the third or detecting stage 80 is a thermionic detector. 35 Amplifiers 65 and 75 are similar and are shown as each comprising an evacuated enclosure, containing a hot cathode or filament 66, 67, respectively, a plate or anode 68, 69, respectively, and a grid or impedance controlling element 70, 71, respectively. Heating current is furnished to filaments 66 and 67 from battery 71', through regulating resistance 72, and plate potential is supplied from battery 73 connected to plate 68 40 through choke impedances 74 and 76, and to plate 69 through choke impedance 77, which oppose the passage through them of variable currents in the output circuits of the respective amplifiers. The variation 45 currents are thus caused to pass through condensers 78 and 79, respectively. A polarizing battery 81 is shown for fixing the normal potential of grid 71 with respect to its filament, and is connected between the 50 grid 71 and the filament 67 through a suitably high resistance 82. A similar battery 81' is shown for fixing the potential of grid 70. The detector 80 is shown as comprising an evacuated enclosure containing the filament 83, heated by current from battery 71' through a regulating resistance, a grid 84 and a plate 85. The external circuit between the plate 85 and filament 83 includes a relay 86 and plate battery 73, and 55 in shunt of this path is the small condenser

87. The normal potential of grid 84 may be fixed by polarizing battery 88 connected to grid 84 and through resistance 89 to filament 83.

With the plug P inserted in the desired 70 jack J₁ or J₂, and with the selective circuits 57, 58, 59, 60 tuned to pass the frequency of the channel from which it is desired to receive, switch S is thrown to the receiving position indicated at R and the incoming 75 waves are impressed upon the amplifying and detecting circuits. The output current from the detector, due to the inductance of the winding of relay 86 and the capacity of the shunting condenser 87, is practically a 80 constant current of a duration corresponding to the length of the wave train received. The length of the wave train may depend upon the time of depression of a key at the distant transmitting station, similar, for 85 instance, in its action to key K. Thus, the relay 86 pulls up and releases its armature in accordance with the actuation of the distant transmitting key or other transmitting 90 arrangement. Contacts for the relay armature are shown adapted to control a suitable local circuit in which may be a sounder or recorder or other receiver. Either or both relay contacts may be used, but a portion of 95 a local circuit including the back contact of the relay is illustrated.

In Fig. 2 a provision for monitoring telephone messages is shown. For selectively transmitting voice modulated carrier waves, the simple tuned circuit connected to the plug P of Fig. 1 is insufficient since the voice-modulated wave comprises a band of frequencies, all of which must be transmitted with substantially uniform efficiency to avoid distortion. A series of band filters F, F₁, F₂, etc., are provided, each so proportioned as to transmit a different carrier wave and the range of frequencies comprised in the wave when it is modulated in accordance with speech. A plug P' is provided on each end of each of said filters and a jack J₃ is in permanent connection with the switch S. When it is desired to communicate telephonically over any channel of either 100 line 1, 2, the filter designed for that channel is selected and its plugs P' are inserted, one in jack J₃ and the other in jack J₁ or J₂ depending on the line to be used. The switch S is thrown into position T if it is desired 105 to transmit or to position R if it is desired to receive. Assuming it is desired to transmit, the condenser 51 is adjusted so that the generator 40 produces current of the carrier frequency desired, and with the switch S in transmitting position, speech is directed 110 against the microphone 90, and as a result of the coupling 91, voice waves are impressed upon the generator circuits and the carrier wave being produced is modulated 115 in accordance with the voice waves. The 120

energy of the generated wave may be controlled by a non-inductive, adjustable resistance 93. The proper filter F, F₁, etc., for the carrier wave employed permits the 5 voice modulated wave to be transmitted to line 1, 2 substantially without distortion. With switch S thrown to the receiving position R, the incoming voice modulated wave is conveyed through the connected band filter 10 to the input of the amplifiers 65 and 75, is detected by detector 80 and rendered audible by receiver 92.

While, for the sake of a complete and clear disclosure, elements have been shown 15 and described specifically, it is to be understood that it is immaterial what particular type of transmitter or generator or receiver or repeater is used and the invention is not to be limited to the particular arrangements shown. Furthermore, certain 20 features of the invention, as will appear in the accompanying claims, are of more general application than for use with a repeater, and the invention is to be limited 25 only by the scope of the appended claims.

What is claimed is:

1. A carrier current signaling system comprising a line having coupling-coil line windings and a net circuit for balancing said line, a monitoring circuit symmetrically associated with said line windings, and carrier current signal transmitting and receiving apparatus for connection to said circuit. 30

2. In a signaling system, lines each having coupling-coil line windings and a net circuit for balancing each line, a single circuit for each said line symmetrically associated with said respective line windings, a transmitter and a receiver for said lines, and 40 means for connecting said transmitter and receiver to any one of said symmetrically associated circuits to the exclusion of the other circuit.

3. In a signaling system employing currents of different frequencies for different 45 transmission channels, a line having coupling-coil line windings and a net circuit for balancing the line as to all said frequencies, a circuit symmetrically associated with said line windings, transmitting and receiving apparatus for connection to said circuit, and means selective as to said frequencies interposed between said circuit and said transmitting and receiving means. 50

5. A carrier current system comprising two line sections terminating in a repeater station, a two-way repeater for repeating between said line sections simultaneously in both directions, and a monitoring system at 55 said repeater station for transmitting or for receiving carrier currents over either line section simultaneously with said two-way repeating.

6. A carrier current repeating system comprising a line circuit having a bridging point

and an artificial circuit in balance with said line as to said bridging point, a repeater connected to said line at said bridging point, and a transmitter for transmitting current to said line and a receiver 70 for receiving current from said line, each arranged for connection in the same manner with said line in balance relation as to said bridging point.

6. A carrier current repeating system 75 comprising a line circuit having a bridging point and an artificial circuit in balance with said line as to said bridging point, a repeater having one side connected to said line at said bridging point, another repeater having 80 its opposite side connected with said line in balanced relation as to said bridging point, and a transmitter and a receiver each arranged for connection in the same manner with said line in balance relation as to said 85 bridging point.

7. In a signal repeating system, a line, a circuit for transmitting currents of different frequencies for different transmission channels having a bridging point and an artificial circuit in balance with said line as to said bridging point for all the frequencies on said line, a repeater for said currents connected to said line at said bridging point, a circuit selective as to said frequencies arranged for connection with said line in balanced relation as to said bridging point, and a transmitter and a receiver arranged for connection with said selective circuit. 100

8. A carrier current signaling system comprising a line having coupling coil line windings and a net for balancing said line, a two-way repeater coupled to said line windings for transferring signaling current in both directions between said line and said repeater, and a separate circuit symmetrically coupled to said line windings for simultaneously transferring current to or receiving current from said line and two-way 105 repeater. 110

9. In a carrier-wave signaling system, lines for transmitting each a plurality of carrier waves differing in frequency, a selective circuit, means for coupling said selective circuit to any one of said lines and for adjusting it to be selective to a desired said carrier wave, a transmitter and a receiver for said lines, and means for coupling said transmitter and said receiver through said 115 selective circuit with said desired line. 120

10. In a carrier-wave signaling system, lines for transmitting each a plurality of carrier waves differing in frequency, a selective circuit, means for coupling said selective circuit to any one of said lines and for adjusting it to be selective to a desired said carrier wave, a transmitter and a receiver for said lines, means for coupling said transmitter and said receiver through said 125 selective circuit with said desired line. 130

tive circuit with said desired line, and means for adjusting said transmitter to the frequency of a desired said carrier wave.

11. In a multiplex signaling system, lines, each having a plurality of discrete communication channels for the transmission of signals therethrough, a selective circuit, means for connecting said circuit to any one of said lines, means in said circuit for selecting any desired communication channel on the desired line, a transmitter and a receiver for said lines, and means for connecting said transmitter and said receiver through said selective circuit to the desired line.
12. In a multiplex signaling system, lines, each having a plurality of discrete communication channels for the transmission of signals therethrough, a selective circuit, means for connecting said circuit to any one of said lines, means in said circuit for selecting any desired communication channel on the desired line, a transmitter and a receiver for said lines, and means for connecting said transmitter and said receiver through said selective circuit to the desired line, and means for adjusting said transmitter for signaling through the selected channel of the desired line.

13. In a carrier-wave transmission system, two line sections, means for transmitting a plurality of carrier currents forming a plurality of communication channels simultaneously on said line sections, two-way repeating means between said line sections for all said channels, and monitoring means for receiving or for transmitting over either line section through any desired said channel.

14. In a carrier-wave transmission system, two line sections for transmitting a plurality of carrier currents forming a plurality of communication channels on said line sections, two-way repeating means between said line sections for all said channels, a circuit, means for connecting said circuit with either line section, means in said circuit for selecting a desired channel on the line section, a transmitter and a receiver, and means for connecting said transmitter and said receiver with said circuit.

15. In a carrier-wave transmission system, two line sections for transmitting a plurality of carrier waves, each modulated in accordance with signals, repeating means between said line sections for repeating said modulated waves, a transmitter and a receiver associated with said repeating means, and connections for utilizing said transmitter and receiver for transmitting or receiving a modulated wave over either said line section.

16. In a carrier-wave transmission system, two line sections for transmitting a plurality of carrier waves, each modulated in accordance with signals, repeating means between said line sections for repeating said modulated waves, a transmitter and a receiver as-

sociated with said repeating means, and connections for utilizing said transmitter and receiver for transmitting or receiving a modulated wave over either said line section while said repeating is in progress.

17. In a signaling system, lines for transmitting currents of different frequencies, a transmitter and a receiver for transmitting and for receiving currents of any of said frequencies, means for connecting said transmitter or said receiver to any one of said lines, and a selective circuit interposed between the transmitter or receiver and the line to which connection is made for permitting the passage of currents of a desired frequency between said transmitter or receiver and the connected line.

18. In a signaling system, a line terminating in coupling line windings and an artificial circuit for balancing said line, a circuit symmetrically associated with said line windings, a loading impedance normally across said circuit, a transmitter and a receiver and a single means for simultaneously removing said loading impedance from said circuit and inserting said transmitter or said receiver into said circuit.

19. In a carrier current signaling system, a line, coils having their windings in series in said line, a net to balance said line, a repeater having an input circuit bridged across the mid-points of said coils, a second repeater having an output circuit including windings inductively associated with certain of said first-mentioned windings, a circuit including windings inductively associated with the others of said first-mentioned windings, and carrier current receiving and transmitting means arranged for connection to said last-mentioned circuit.

20. In a signaling system, a line having coupling-coil line windings and a net circuit for balancing said line, a circuit symmetrically associated with said line windings, a loading impedance normally in said circuit, signaling means for said line, and single means for simultaneously connecting said signaling means to said circuit and removing said loading impedance from said circuit.

21. In a signaling system, lines for the simultaneous transmission of currents representing a plurality of signals, repeating means between said lines for repeating all said currents, and monitoring means associated with the repeating means for registering any one of said signals to the exclusion of other signals.

22. In a signaling system, lines for the simultaneous transmission of currents representing a plurality of signals, repeating means between said lines for repeating all said currents, and monitoring means associated with the repeating means for registering any of said signals to the exclusion of

- 3 other signals and for transmitting signals over said lines.
23. In a signaling system, lines for the simultaneous transmission of currents representing a plurality of messages, a repeating station through which said currents are simultaneously repeated between said lines, and monitoring means at the repeating station for registering a desired one of said messages during its repetition.
24. In a signaling system, lines for the simultaneous transmission of currents representing a plurality of messages, a repeating station through which said currents are simultaneously repeated between said lines, and monitoring means at the repeating station for registering a desired one of said messages during its repetition and for transmitting over said lines.
25. In a signaling system, lines for the simultaneous transmission of currents in both directions representing a plurality of messages in each direction, a repeating station through which said currents are simultaneously repeated in both directions between said lines, monitoring means at said repeating station for registering any one of said messages, and means for selectively transmitting currents representing any one of said messages from said lines to said monitoring means.
26. In a signaling system, lines for the simultaneous transmission of currents in both directions representing a plurality of messages in each direction, a repeating station through which said currents are simultaneously repeated in both directions between said lines, monitoring means at said repeating station for registering any one of said messages and for transmitting over said lines, and means for selectively transmitting currents representing any one of said messages between said lines and said monitoring means.
27. A line for the transmission of currents of different frequencies, a generator for said currents, filtering circuits each for transmitting current of a given said frequency, and switching means for connecting said generator to said line through any one of said filtering circuits.
28. A line for the transmission of voice-modulated current waves, a transmitter and a receiver for said waves, band filters for selectively transmitting a said modulated wave, and means for connecting said transmitter and said receiver to said line through any one of said filters.
29. A line for transmitting a plurality of modulated current waves simultaneously, a filter for each said wave, a transmitter and a receiver for said modulated waves, and means for connecting said transmitter and said receiver to said line through any selected one of said filters.
30. A line for the transmission of modulated current waves of different frequencies, a transmitter and a receiver for all said waves, a selective path for each said modulated wave, and means for associating said transmitter and said receiver with said line through any one of said selective paths.
31. In a telephone system, lines for the simultaneous transmission of currents representing a plurality of conversations, repeating means between said lines for repeating said currents, and monitoring means for receiving currents representing any one of said conversations and for transmitting currents over said lines.
32. In a telephone system, lines for the simultaneous transmission of currents representing a plurality of conversations, repeating means between said lines for repeating said currents, a receiver, and means for selecting the currents representing any single said conversation and for transmitting them between said lines and said receiver.
33. A signaling system comprising a line for the transmission of current waves of different frequencies, a receiver for all said waves, means included in said receiver for changing the frequencies of all said waves, a selective path for each of said waves, and means for connecting said receiver with said line through any one of said selective paths.
34. A signaling system comprising a plurality of lines for the transmission of carrier waves of different frequencies, a receiver for all said waves, a selective path for each of said waves and means for connecting said receiver with any one of said lines through any one of said selective paths.
35. A transmission circuit, means to transmit messages thereover, a monitoring operator's circuit for supervising the messages transmitted over said transmission circuit, said monitoring circuit comprising a source of oscillations adapted to supply carrier oscillations of different frequencies, frequency selective devices, and means for associating any one of said selective devices with said source.
36. A transmission circuit, means to transmit messages thereover, a monitoring operator's circuit for supervising the messages transmitted over said transmission circuit, said monitoring circuit comprising a source of oscillations adapted to supply carrier oscillations of different frequencies, cord circuits including devices selective of said different frequencies, and means for associating any one of said cord circuits with said source.
37. A transmission circuit, means to transmit messages thereover, a monitoring operator's circuit for supervising the messages transmitted over said transmission circuit, said monitoring circuit comprising a receiving circuit including an amplifier and de-

tector, cord circuits including devices selective of different frequencies, and means for associating any one of said cord circuits with said receiving circuit.

5 38. A line for transmission of voice modulated current waves, a transmitter and a receiver for said waves, a plurality of cord circuits having band filters for selectively transmitting a said modulated wave and 10 means for connecting said transmitter and receiver with any one of said cord circuits.

15 39. A telephone system comprising a plurality of cord circuits each provided with selective means, each of said selective means adapted to pass a different range of frequencies than the others and a plurality of lines to any one of which any one of said circuits is adapted to be connected.

20 40. A signal system comprising a plurality of lines having a plurality of carrier current channels superimposed upon one another on each line, means at an intermediate station for connecting said lines and supervising means at said station.

25 41. A signal system comprising a plurality of lines, each adapted to transmit a plurality of corresponding different frequency carrier currents, means at an intermediate station for connecting said lines 30 and means at said station for supervising

transmission over any carrier frequency channel.

42. A carrier current system for connecting a plurality of terminal stations through an intermediate station comprising an intermediate station, a plurality of lines between said terminal stations and said intermediate station, means associated with each line for permitting a plurality of different frequency carrier currents to be transmitted thereover, 40 means at said intermediate station for interconnecting said lines and supervising means at said intermediate station.

45 43. A carrier current system for connecting a plurality of terminal stations through an intermediate station comprising an intermediate station, a plurality of lines between the terminal stations and the intermediate station, means associated with each line for permitting a plurality of different frequency 50 carrier currents to be transmitted thereover, means at the intermediate station for interconnecting said lines, and means at said intermediate station for supervising transmission over any carrier frequency channel 55 individually.

In witness whereof, I hereunto subscribe my name this seventh day of August A. D., 1919.

BURTON W. KENDALL.
